DESIGN FOR A BOX

Rene Tricard, Paris, France, assignor to Lentheric
Incorporated, New York, N. Y., a corporation
of New York

Application May 12, 1933, Serial No. 48,088

Term of patent 14 years

To all whom it may concern:

Be it known that I, RENE TRICARD, a citizen of France, residing at Paris, France, have invented a new, original, and ornamental Design for a Box, of which the following is a specification, reference being had to the accompanying drawing, forming a part thereof.

In the drawing of the box:

Figure 1 is a top view; and

Figure 2 is a front view.

All four vertical sides are substantially the same.

The dominant features of the design comprise: borders of a contrasting color on the top and on each vertical side, such borders being narrow except those at the upper horizontal edges of the vertical sides; and a base projecting a short distance from each vertical side, the vertical faces of the base being of the same contrasting color.

I claim:

The ornamental design for a box substantially as shown and described.

RENE TRICARD.
